UNITED STATES PATENT OFFICE.

JOHN G. L. ANDERSON, OF PROVIDENCE, RHODE ISLAND.

PROPELLING ATTACHMENT FOR LIFE-PRESERVERS.

1,103,729.

Specification of Letters Patent. Patented July 14, 1914.

Application filed January 7, 1913. Serial No. 740,671.

To all whom it may concern:

Be it known that I, JOHN G. L. ANDERSON, a citizen of the United States, residing at Providence, in the county of Providence and 5 State of Rhode Island, have invented certain new and useful Improvements in Propelling Attachments for Life-Preservers, of which the following is a specification.

This invention relates to an improvement 10 in propelling attachments for life preservers.

The primary object of the invention is to provide a propelling device which may be attached to life preservers by means of which the wearer may propel the device through 15 the water.

A further object of the invention is to provide a construction which may be attached to life belts such as are now in use without altering their construction or interfering with their operation as life preservers. 20

A still further object of the invention is to provide a mechanism which may be manually operated in a simple and convenient manner while the life belt is in position on 25 the body.

A further object of the invention is to so arrange the propeller that it will draw the wearer forward in the water and have a lifting tendency as well as a propelling 30 tendency.

Another object of the invention is to provide a construction which will be comparatively light, and which, while forming an effectual propelling mechanism, will not 35 materially add to the weight of the life preserver.

A further object of the invention is to provide a construction in which the gearing of the propelling mechanism is at all times 40 accessible for the purpose of lubrication and repair.

In the drawings: Figure 1 is a disassembled perspective view of the apparatus and a life belt of the usual construction; Fig. 2 45 is a vertical section showing the device arranged on a life belt; Fig. 3 is a perspective view showing a modified form of belt; Fig. 4 is a vertical section of a slightly modified form of propelling mechanism; Fig. 5 is a perspective view of the propelling device shown in Fig. 4. Fig. 6 is a detail view showing the arrangement of the handle and crank.

In the drawings, 10 designates a life belt 55 of the usual construction which consists of the cork sections 11 and the straps 11' by

means of which the device is supported on the body. The invention broadly contemplates a construction which may be attached to a life belt without altering the construction of the belt, but in the form shown in Fig. 1, one of the cork sections 11 is provided with a vertical opening 12 which receives the attaching rod of the propelling mechanism. The propelling mechanism 60 consists of a supporting structure 13, which is of a length slightly greater than that of the width of the usual life belt, being provided with a gear housing 14 through which extends a shaft 15 on which the gear 16 is keyed.

The shaft 15 extends through the housing and is rotated by means of a crank 17. A shaft 18 is rotatably supported by the portion 19 of the casing, a gear 20 being mounted on said shaft, said gear meshing with the gear 16. A gear 21 is mounted on the terminal of the shaft 18 remote from the gear 20, said gear being arranged within the chamber 22 of the supporting member 13. A shaft 23 is supported by the member 13 at right angles to the shaft 18, the terminal 24 of said shaft extending within the obliquely disposed opening 25 of the member 13. A gear 26 is mounted on the terminal 24 of the shaft 23 remote from the opening 25, said gear meshing with the gear 21 of the shaft 18. It will be noted from this construction that as the crank 17 is rotated, movement will be imparted to the shaft 23 85 through the shaft 18.

A propeller 27 is mounted on the shaft 23, said propeller being disposed obliquely with respect to the base 28 of the support member 13. This arrangement of the propeller 95 produces the forward movement of the mechanism, the mechanism being secured to the front of the life belt where the crank 17 may be conveniently manipulated by the wearer. The propeller is covered by a guard 29 formed of wire mesh, this guard preventing the hands of the wearer from contacting with the blades of the propeller.

The device may be secured to a belt in any suitable manner, and as illustrated in Figs. 1 and 2, the base 28 is provided with an extension 30 which is provided with an aperture 31, a pin 32 passing through this extension. This pin pivotally supports a rod 33, the terminal 34 of which is screw threaded 105 and receives a nut 35. The edge portion 36 of the member 13 at a point immediately be-

low the casing 14 forms a shoulder 37 on which is arranged a keeper 38, the slot 39 of which receives the rod 33, the nut 35 being tightened to engage the keeper to securely hold the rod against displacement. It will be noted by this construction that the portion 40 of the life preserver between the sections 11 may be placed between the rod and the edge 36 of the member 13 and 10 the rod 33 inserted within the slot 39 of the keeper 38 and securely locked against displacement, the device thus being secured to the life belt.

Curved supporting arms 41 are secured 15 to the rear wall of the edge 36 of the member 13, said arms contacting with the sections 11 to support the member 13 against movement. While this construction is adapted for attachment to life belts of the 20 usual construction, it will be noted that a more convenient method of attaching is to provide one of the cork sections with an opening 12 through which the rod may be inserted, the rod then being clamped to the keeper 38. In this construction, the keeper and the extension 30 are prevented from 25 coming in contact with the body of the wearer.

In the form shown in Fig. 4, the supporting member consists of a metallic frame 42 which is preferably formed of aluminum. This frame 42 embraces panels 43 of cork, the frame being of the same configuration as the supporting member 13. In this form, 30 the gear 44 is supported within the casing 45, the shaft 46 being supported within a bearing 47 which is formed integral with the frame. A bearing 48 supports the shaft 49, the shafts being provided with meshing 35 gears whereby the propeller, which is mounted on the shaft 48, may be driven. The frame is formed with an opening 49' for the propeller, and a guard 50 of wire fabric embraces the propeller as in the preferred form.

The construction illustrated in Figs. 4 and 5, is designed for use with inflatable life belts, such as that illustrated in Fig. 3, the life belt comprising inflatable sections 51 50 and 52 and an intermediate section 53, which may be either inflatable or formed of cork. This section is formed with a vertically disposed opening 54 which receives a rod 55, the propelling mechanism in this manner being clamped to the belt. It will be noted that a construction of this character will be light, the only metallic members being the frame and the gearing, the panels being formed of cork, there being suitable removable panels 56 which may be formed of aluminum which cover the gears.

Attention is called to the fact that in the practical use of the invention, the supporting member 13 may be readily employed to 60 steer the life belt making it readily possible

for the operator of the propelling mechanism to easily proceed in any desired direction.

It will be noted that a device of this character may be readily attached to life belts such as are now in use as well as those illustrated in the accompanying drawings, and that it provides an effectual propelling means for the life preserver without materially adding to its weight, the propelling mechanism being such as may be operated with little exertion. It will also be noted that the propeller is so disposed as to create a lifting tendency as well as to propel the device through the water.

It will be seen that the construction is such as may be easily and economically manufactured and that the various parts may be readily assembled.

Having thus described the invention, what I claim as new and desire to secure by Letters Patent is:—

1. A propelling mechanism for life belts comprising a supporting member, means for attaching the supporting member to the belt, a housing arranged on the supporting member, a gear arranged in said housing, shafts disposed at right angles to each other, meshing gears carried by said shafts, the first-mentioned gear imparting motion to said shafts, said supporting member being formed with an obliquely disposed opening, a propeller mounted on one of said shafts and disposed in said opening, and means for rotating the first mentioned gear.

2. A propelling attachment for life belts comprising a supporting member, a manually operated propelling mechanism carried by said member, a rod hingedly supported by the member and disposed to clamp the member to the belt, a keeper arranged on the supporting member and disposed to engage the free end of said rod.

3. A propelling attachment for life belts comprising a frame, a housing supported by said frame, a gear arranged in said housing, a shaft supported by the frame, a gear carried by said shaft and meshing with the first-mentioned gear, a second shaft supported by said housing at right angles to the first-mentioned shaft, meshing gears carried by said shafts, an obliquely disposed opening formed in said frame, a propeller mounted on the second-mentioned shaft and disposed in said opening, panels formed of cork and secured to said frame, metallic plates secured to the cork panels and inclosing said shafts, and means for operating the first-mentioned gear to drive said propeller.

4. A propelling mechanism for life belts comprising a supporting member, pivoted means carried by the supporting member and disposed to embrace the belt, said supporting member consisting of a vertically disposed casing formed with an opening ar-

ranged obliquely with respect to the belt, a propeller mounted for rotation within said opening, and means for rotating said propeller.

5. A propelling mechanism for life belts comprising a supporting member including spaced plates constituting a housing, a gear wheel arranged within said housing, means for operating said gear wheel, a shaft supported within the housing and driven by said gear wheel, a second shaft disposed at right angles to the first mentioned shaft and driven by the same, said housing being provided with an opening which slopes from the upper edge of the housing which is secured to the belt downwardly to the lower unattached edge of the housing, and a propeller carried on the last mentioned shaft and disposed within said opening.

10. A propelling mechanism for life belts including a supporting member having a base, a propeller rotatably mounted on the supporting member within an opening therein and disposed obliquely with respect to the base of said member, the propeller extending outwardly and downwardly from the body of the wearer, whereby the same, when rotated, will exert a lifting motion to the body, and means for attaching the supporting member to a life belt.

25. A propelling mechanism for life belts including a supporting frame, a propelling mechanism carried thereby, removable panels carried by the frame and constituting a housing for the propelling mechanism, and means for attaching the frame to a life belt.

30. The combination with a life belt, of a propelling means therefor including a rela-

tively thin supporting frame disposed vertically of the belt, said frame being adapted to steer the belt when in use, and propelling mechanism carried by the frame.

40. 9. A propelling mechanism for life belts including a supporting member, propelling mechanism mounted thereon, arms formed on the supporting member, and means carried by said member for clamping a life belt against said arms.

45. 10. A propelling mechanism for life belts including a supporting member, a propeller carried thereby and mounted within an opening in said member, said propeller including blades which in one position are housed within the supporting member, means for rotating the propeller, and means for attaching the supporting member to a life belt.

50. 11. A propelling mechanism for life belts including a relatively thin vertically disposed supporting member, a propeller carried thereby and mounted to rotate within a transverse opening in said member, means for rotating the propeller, and means for attaching the supporting member to a life belt.

55. 12. The combination with a life belt, of a propelling means therefor including a relatively thin supporting member disposed vertically of the belt, and a propelling mechanism carried by said member.

60. In testimony whereof I affix my signature in presence of two witnesses.
